(57) **CLAIM**

The ornamental design for a watch, as shown and described.

DESCRIPTION

FIG. 1 is a front elevational view of a watch showing my new design;

FIG. 2 is a bottom front perspective view thereof;

FIG. 3 is a left front perspective view thereof;

FIG. 4 is a left rear perspective view thereof; and,

FIG. 5 is a right front perspective view thereof.

The structural features depicted by broken lines in the drawings have been shown for the purpose of illustrating portions of the watch that form no part of the claimed design.

1 Claim, 5 Drawing Sheets
